Primary Examiner — Mark A Goodwin*Assistant Examiner* — Benjamin M Weeks(74) *Attorney, Agent, or Firm* — Finnegan, Henderson, Farabow, Garrett & Dunner, LLC(57) **CLAIM**

The ornamental design for a cabin of a reclaimer, as shown and described.

DESCRIPTION

FIG. 1 is a front, top, left perspective view of a cabin of a reclaimer showing the new design;

FIG. 2 is a rear, top, right perspective view thereof;

FIG. 3 is rear, bottom, left perspective view thereof;

FIG. 4 is a front elevation view thereof;

FIG. 5 is a left side view thereof;

FIG. 6 is a right side view thereof;

FIG. 7 is a rear elevation view thereof;

FIG. 8 is a bottom plan view thereof;

FIG. 9 is a top plan view thereof; and,

FIG. 10 is another front elevation view thereof with the remainder of the reclaimer shown as unclaimed environmental subject matter.

The broken lines of even length shown in the drawings illustrate environmental structure and form no part of the claimed design.
